CENTRIFUGAL HYDRO-EXTRACTOR

Armand Bailly, Brussels, Belgium; vested in the
Alien Property CustodianApplication February 8, 1940, Serial No. 317,942
In Belgium February 8, 1939

8 Claims. (Cl. 210—169)

My invention relates to improvements in the centrifugal hydro-extractor disclosed in the main patent application Serial No. 184,304, and comprising essentially a conical filtering basket and a drum mounted coaxially within the said basket, the said drum being capable of rotating at a speed different from that of the basket and being provided with annular projections or webs formed with gaps, which webs extend up to a point adjacent the filtering wall and are effective in restraining the flow of the material, as the latter moves along the filtering wall. Impervious zones may be provided in the filtering wall opposite the rims of the annular webs, which latter may be connected to each other by auxiliary webs.

The main object of the present invention is to improve the operation of the device and to ensure a rational extraction of the material treated. More particularly, the present invention makes it possible to overcome the lack of balance in the revolving assembly; to eliminate deposits from the material upon the rotating parts, through the injection of steam or the like; and, moreover, to avoid any detrimental moistening of the final product.

The special features and numerous advantages of the present invention will be apparent from the following statement wherein a few embodiments of the extractor according to the present invention are described with reference to the accompanying diagrammatical drawing in which:

Fig. 1 is an elevation, partly in section, of a centrifugal hydro-extractor;

Fig. 2 is a plan view, partly in section, of the extractor;

Fig. 3 is an elevation, partly in section, of a modified extractor;

Figs. 4 and 5 are fragmentary views in axial section and in elevation respectively, of another modification.

The extractor includes a basket 2 associated with a filtering or pervious wall 3 and mounted on a rotary shaft 6 by means of a flange 5, the whole assembly being enclosed in a housing 1. On a shaft 4 there is mounted a drum 7 bearing outer annular webs 8, 9, 10 provided with circumferentially staggered gaps 11, 12, 13 allowing the passage of the material to be treated, which has a tendency to slip along the wall 3, but is retained for a suitable time by the webs 8, 9, 10. The material to be treated is supplied through the tube 15 to the distributor 14 which may consist of an annular apron mem-

ber rigid with the drum. Advantageously, impervious strips 39, 40, 41 are inserted into the wall 3, opposite the webs 8, 9, 10.

The shafts 4 and 6 may be rotated at different speeds through any suitable means (not shown).

The extracted material is discharged through the collector 16, while the liquid flows off through the duct 17.

When certain substances, for example, saline 10 solutions, such as solutions of ammonium sulphate, sodium nitrate, etc., are under treatment, the filtering wall, which is generally formed of wire fabric, may get rapidly clogged on account of solid particles that become deposited, 15 more specially by reason of the precipitation of the salts on the wires of the metal fabric due to the cooling down of the mother-liquors.

According to this invention, such clogging may be avoided by washing the filtering wall, preferably in a continuous way, by means of jets, directed against the said filtering wall, of a medium, for instance steam or water, capable of removing, for example by way of dissolution, the particles deposited thereon, the said jets being delivered from injector devices revolving with the drum and lodged in the various annular compartments determined by the annular webs 8, 9, 10.

The steam or water injector devices comprise 30 for example tubes 29, 30, 31 provided with bore holes or slots and supplied with washing medium through pipes 32, 33, 34, connected, via bore holes in the shaft 4, with a longitudinal bore 35 formed in the said shaft and communicating with a source of steam or water.

The steam or water injector devices may be located adjacent the "trailing" edges (it is to say the edges which are second to pass opposite a given point of the basket on account of the relative movement of the drum and the basket) of the gaps across which the material being treated flows out of the annular compartments. Consequently, the stream of injected medium is directed against a momentarily uncovered portion of the wall 3, which makes possible an efficient washing of the said wall without at the same time wetting the material. Webs 36, 37, 38 and 23, 24, 25 may be provided on one or on either side of the tubes 29, 30, 31, in order to better isolate the said tubes, the webs 23, 24, 25 serving moreover to detach the particles that may adhere accidentally to the inner face of the wall 3, and may constitute an unbalanced 45 weight. Alternately, the tubes 29, 30, 31 may be

incorporated each in one of the webs interposed between the annular members 8, 9, 10.

However, in the treatment of certain materials, such as sugar, it is desirable to wet the material in the course of treatment, in order to keep it at a suitable degree of fluidity. To this end, and according to my invention, washing medium, for example, steam or water, may be injected in one or more points by means of devices arranged to revolve with the drum and which, therefore, move slowly with respect to the basket and perform their washing action for a sufficient period of time. If desired, such washing may be combined with the injection effected via the tubes 29, 30, 31, for example by connecting to the latter further perforated or slotted tubes, which form the prolongation of the tubes 29, 30, 31 and extend up to the gaps across which the material under treatment enters the annular compartment considered. Fig. 2 shows one such washing tube 42, in the intermediate annular compartment. Similar tubes may be provided at the entrance to each compartment, and the transverse webs such as 24, 37 may be dispensed with.

According to my invention, as illustrated in Fig. 3, the basket may be provided with a shoulder adjacent the root of the strips 39, 40, and 41 respectively, so as to present a plurality of stepped cones. This is effective in an increase in the capacity of the successive compartments. Owing to this arrangement, the axial length of the said compartments, and consequently of the basket, may be shortened, without reducing the capacity of the extractor. The resulting reduction in the axial length of the non-supported portion of the movable assembly is a highly desirable feature.

It has further been found that the cooling down of the material as it enters the distributor 14 may cause the formation of crusts, which would finally clog the outlets from the distributor with the result that the extracting process will be arrested.

To avoid this drawback, steam or the like may be injected into the distributor 14 via a fixed pipe 43, the jet of steam sweeping the whole of the inner surface of the rotary distributor. With the same object in view and, if desired, in addition to the pipe 43, a shell or jacket supplied with steam or the like may be provided around the distributor 14. Such jacket may be formed, for example, by a chamber 45 interposed in the flow of the pipes such as 33, 34 (Figs. 4 and 5).

The distributor 14 may be constituted by a simple annular apron member. However, as shown in Figs. 4 and 5, the distributor may be made for example in the shape of a frusto-conical basin formed with two arcuate hollow arms 46, 47 extending therefrom and discharging at two diametrically opposed points, 48, 49 at the end of smallest diameter of the basket 2.

It will be apparent that the various injections of steam or other washing media promote the production of wet vapours in the space between the drum and the basket. Under the effect of the centrifugal force, such vapours travel towards the discharge end of the extractor and may moisten the final product.

In order to prevent liquid or even steam from being discharged together with the final product, the collector 16 is spaced a certain distance apart from the housing 1, and the material which has undergone the liquid-extraction process is discharged via nozzles 27 having one end connected

with the discharge openings of the extractor, while their other ends project into an annular opening 28 of the collector 16.

In order to prevent wet vapours that may escape past the nozzles 27, especially when large quantities of steam are injected, from entering the collector 16, provision is made at the free end of each nozzle 27, of a blade 44, the concave face of the blades looking in the direction of the rotation of the revolving assembly. Owing to the action of these blades, the air contained in the collector 16 enters with force into the nozzles 27, thus preventing any escape of steam therefrom, without interfering with the discharge of the product.

What I claim is:

1. In a centrifugal extractor, the combination with a conical basket having a screen, of a conical drum within and axially aligned with said basket and having circumferential webs projecting in direction towards the basket, means for rotating the drum and basket at relatively different speeds, the annular webs on the drum being provided with gaps which are circumferentially offset from each other, circumferential ribs on the screen of the basket projecting in direction towards the webs and in close opposition thereto whereby annular compartments are provided between said webs, ribs, drum and basket respectively, means for supplying the material to be treated between the drum and the basket, and means for directing jets of liquid against the gaps only of the drum, whereby the material in the annular compartments is flowed through said gaps.

2. In a centrifugal extractor, the combination with a conical basket having a screen thereon, of a conical drum within and in axial alignment with said screen, annular webs projecting from the drum in direction towards the screen of the basket, said webs being provided with gaps circumferentially staggered on the drum, annular ribs on the screen of the basket projecting in direction towards the webs and in close opposition thereto, means for supplying the material to be treated between the drum and the basket, means for rotating the drum and basket at relatively different speeds, and means adjacent the trailing edge of each gap for supplying a stream of fluid into the space between the webs and ribs, whereby the material accumulated in each annular space formed by said webs and ribs is sloughed through the gap into the next adjacent annular compartment between drum and basket.

3. In an extractor of the character described, the combination of a conical basket having a screen, a drum within and in axial alignment therewith, a plurality of annular webs projecting from the drum in direction towards the basket, said webs being provided with gaps circumferentially offset from each other, a plurality of ribs on the screen of the basket in opposition to said webs and projecting towards the same, whereby between said webs, ribs, drum and basket annular compartments are formed, means for supplying the material to be treated through the drum into the space between the drum and the basket, means for imparting relatively different rotary speeds to said basket and said drum, and means in the form of water pipes extending axially between two webs of the drum adjacent each of the gaps for supplying washing fluid to the material confined in the respective compartment, whereby the material is sloughed through the gap

into the next adjacent annular compartment of the drum.

4. A centrifugal extractor, including in combination a conical basket provided with a screen, a conical drum within and in axial alinement with said basket, a plurality of circumferential webs projecting from the surface of the drum in direction towards the basket, said annular webs being provided with gaps circumferentially staggered thereon, a plurality of annular ribs on the screen surface projecting in direction towards the drum and in close opposition to the free ends of the webs of the drum, whereby a plurality of annular compartments are provided, each compartment being adapted to communication with the next adjacent compartment through one of the gaps, means for rotating the basket and drum at relatively different speeds, means for supplying the material to be treated to the space between the drum and the screen, and means rotating with the drum and confined on the drum to zones adjacent the gaps for supplying washing fluid to the annular compartments for sloughing the material in said compartments directly through said gaps.

5. An extractor of the character described, comprising in combination with a conical basket having a screen, a conical drum within and in axial alinement with said basket, a plurality of annular webs projecting from the surface of the drum in direction towards said screen, said webs having gaps which are circumferentially staggered relatively to each other, a plurality of annular ribs on the surface of the screen in opposition to and projecting closely to the free ends of the webs of the drum, whereby a plurality of annular compartments are formed communicating with each other through the staggered gaps, means for rotating said basket and drum at relatively different speeds, means for supplying the material to be treated between the drum and basket, and means extending in each compartment across the gap and across the compartment adjacent the gap for supplying washing fluid to the compartment for sloughing off the material in said compartment through the gap to the next adjacent compartment without affecting the material in said annular compartment remote from said gap.

6. In an extractor of the character described, the combination of a conical basket having a screen thereon, a conical drum within and in axial alinement with said basket, a plurality of annular webs on the surface of the drum projecting in direction towards the basket, said webs being provided with gaps which are circumfer-

tially offset relatively to each other, a plurality of ribs projecting from the screen in direction towards the drum in close opposition to the ends of the annular webs, whereby a plurality of annular compartments are formed between drum and basket, said webs and ribs respectively, means for supplying material to the space between said drum and basket, means for rotating said drum and basket at relatively different speeds, and means in the form of pipes rotating with the drum and extending in the compartments across the gaps thereof and adjacent the trailing edge of the gaps for supplying washing fluid to the material in said compartment for sloughing it through the gap to the next adjacent compartment.

7. In a centrifugal extractor of the character described, the combination of a conical basket having a screen thereon, the screen being assembled of a plurality of alined circular conical portions, the smaller diameter of each conical portion being greater than the greater diameter of the next adjacent conical portion in direction towards the apex, circumferential shoulders between each two adjacent conical portions, a conical drum within and in axial alinement with the basket, means for rotating said drum and basket at relatively different spaces, means for supplying the material to be treated between said drum and basket, a plurality of webs projecting from the surface of the drum in direction towards the basket and in opposition to the circumferential shoulders thereof, and means for supplying washing fluid to said compartments for sloughing the material from the compartments.

8. In an extractor of the character described, the combination of a conical basket having a screen provided with circumferential shoulders between adjacent conical screen portions of different diameters, a drum within and in axial alinement with said screen, means for imparting relatively different speeds to said drum and basket, a plurality of webs projecting from said drum in direction towards the basket, said webs being provided with gaps circumferentially staggered thereon, means for supplying material to the space between the drum and the basket, and annular ribs at the shoulder portions of the screen projecting in opposition to the free ends of the webs and close to said webs, whereby a plurality of annular compartments are formed between said drum and screen sections and said webs and ribs, and means for supplying said annular compartments with washing fluid adjacent said gaps only on the drum.

ARMAND BAILLY.
